UNITED STATES PATENT OFFICE.

HENRY RAPP, OF HILTON, NEW JERSEY.

TOBACCO PIPE.

Application filed October 7, 1921. Serial No. 505,992.

To all whom it may concern:

Be it known that I, HENRY RAPP, a citizen of the United States, and a resident of Hilton, in the county of Essex and State of New Jersey, have invented new and useful Improvements in Tobacco Pipes, of which the following is a specification.

One object of this invention is to provide a tobacco pipe embodying novel features of construction and having the smoke conduit from the bowl formed of two sections, one of which forms the bottom of the bowl and is removable for cleaning and the other of which comprises a tube removably mounted in the stem of the pipe and detachably connected at one end to said first-mentioned section, whereby the smoke conduit can be easily kept clean and prevented from becoming saturated with tobacco juice and saliva. 10 Further objects of the invention are to provide a tobacco pipe having a removable plug in the bottom of the bowl thereof with one end projecting into the stem of the bowl and formed with a passage communicating between the bowl and the stem, and a tube removably mounted in the stem or mouthpiece of the pipe, said end of the said plug being adapted to frictionally and removably receive one end of said tube; to provide such a 15 tobacco pipe having a non-absorbent plug and a renewable tube in the stem, whereby the smoke conduit at the bottom of the bowl and in the stem of the bowl is prevented from becoming saturated with tobacco juice and the said tube in the stem can be destroyed and replaced by a clean tube, and to obtain other results and advantages as 20 may be brought out by the following description.

40 Referring to the accompanying drawings, in which like numerals of reference indicate the same parts throughout the several views,

Figure 1 is a vertical longitudinal sectional view through a tobacco pipe embodying my invention;

Figure 2 is a transverse vertical sectional view through the bowl thereof, taken on the line 2—2 of Fig. 1;

50 Figure 3 is a transverse sectional view through the stem of the bowl, taken on the line 3—3 of Fig. 1, and

Figure 4 is a detached view partially in section of a modification in the connection 55 of the plug and the tube.

In the drawings the reference character 1

designates the bowl of a pipe which is formed with the usual integral laterally projecting stem 2 which is provided with an axial passage 3. My invention comprises a 60 cylindrical plug 4 formed of non-absorbent material which is mounted in a passage 5 transverse of the bottom of the bowl 1 and in alinement with the passage 3 of the stem of the bowl, said plug being provided 65 with a finger piece or head 6 for removing the same from the passage 5. The plug 4 is formed with an axial smoke passage 7 and has one side thereof cut away as at 70 8 to form communication between the passage 7 and the bowl of the pipe, as shown in Figures 1 and 2. The inner end of the plug is formed with a reduced axial extension 9 which projects into the passage 3, and the said passage is formed with an 75 annular shoulder 10 to limit the insertion of the plug 4 into the passage 3.

The stem or mouthpiece 11 of the pipe is removably fitted into the end of the stem 2 of the bowl, and is formed with a bore 12 80 adapted to removably receive a tube 13 which projects from the end of the stem and is adapted to frictionally fit over the reduced extension 9 of the plug 4, as shown in Figure 1, when the stem 11 is in position in the pipe. The bore 12 is provided at its outer end with a shoulder 14 which limits the insertion of the tube 13 into the stem. The inner end of the plug 4 is preferably formed inwardly of the extension 90 9 with a tapered portion 15 against which the end of the tube 13 is slipped so as to form a tight connection between the tube 13 and the plug 4.

With this construction, the non-absorbent 95 plug 4 prevents the bottom of the bowl 1 from becoming saturated with tobacco juice, and the plug can be easily removed for cleaning the bowl. The moisture in the smoke collects on the walls of the tube 13, 100 which is formed of inexpensive material, such as paper, and can easily be removed from the stem 11, discarded and replaced by a new tube to clean the stem of the pipe. The connection of the tube 13 with the ex- 105 tension 9 of the plug 4 is a sliding frictional fit, so that to remove the tube 13 it is merely necessary to pull the stem 11 out of the stem 2 of the bowl and slide the tube from the bore 12.

110 A modified construction is shown in Figure 4 in which the inner end of the plug 4 is

formed with an enlarged opening 16 to frictionally receive the end of the tube 13 within itself.

The pipe can be kept clean and sanitary by simply removing the plug 4 and cleaning the same and replacing the tube 13, and it will be noted that the smoke conduit consisting of the plug 4 and the tube 13 is thus prevented from becoming saturated with tobacco juice and saliva.

Having thus described the invention, what I claim is:

1. In a tobacco pipe, the combination with a bowl having a stem and an opening arranged transversely of the bottom of said bowl and through said stem, and a mouthpiece removably mounted in the end of said stem, of a plug removably mounted in said opening in the bowl and having a passage communicating with said bowl and said stem, and a tube removably mounted in said mouthpiece and detachably connected at one end to said plug, whereby the passage in said plug and said tube form a continuous smoke conduit.

2. In a tobacco pipe, the combination with a bowl having a stem and an opening arranged transversely of the bottom of said bowl and through said stem, and a mouthpiece removably mounted in the end of said stem, of a plug removably mounted in said opening in the bowl and having a passage communicating with said bowl and said stem, and in axial alinement with said mouthpiece, and a tube removably mounted axially in said mouthpiece and having a detachably longitudinally sliding frictional connection with the inner end of said plug.

3. In a tobacco pipe, the combination with a bowl having a stem and an opening arranged transversely of the bottom of said bowl and through said stem, and a mouthpiece removably mounted in the end of said stem, of a plug removably mounted in said

opening in the bowl and having a passage 45 communicating with said bowl and said stem, the inner end of said plug having an axial reduced portion, and a tube removably mounted in said mouthpiece and having one end fitted over said reduced extension 50 on the said plug.

4. In a tobacco pipe, the combination with a bowl having a stem and an opening arranged transversely of the bottom of said bowl and through said stem, and a mouthpiece removably mounted in the end of said stem, of a plug removably mounted in said opening in the bowl and having a passage 55 communicating with said bowl and said stem, the inner end of said plug having an axial reduced portion, and a tube removably mounted in said mouthpiece and having one end detachably and frictionally slipped over said reduced extension 60 on the plug, whereby the passage in said plug and said tube form a continuous smoke conduit.

5. In a tobacco pipe, the combination with a bowl having a stem and an opening arranged transversely of the bottom of said bowl and through said stem, of a mouthpiece removably connected to the end of said stem and having an axial bore therein formed with a shoulder, a plug removably mounted in said opening in the bowl and 70 having an axial passage communicating with said bowl and said stem, the inner end of said plug being tapered and terminating in a reduced axial extension, and a tube removably mounted in said bore in the 75 mouthpiece and engaging at one end said shoulder, the other end of said tube being adapted to frictionally slip over said extension on the plug and against the tapered end thereof as the mouthpiece is connected 80 to said stem.

HENRY RAPP.
